MARIONETTE FOR NARROW WARE LOOMS

Frank W. Preston, Paterson, N. J.

Application May 6, 1938, Serial No. 206,321

4 Claims. (Cl. 139—137)

This invention relates to means for selecting and driving the shuttles in a narrow-ware loom having its shuttles superposed, as usually in superposed banks, i. e., a number of shuttles to 5 each bank; and it has reference particularly to that type of such means known as a marionette. Heretofore when the loom was equipped with four superposed shuttles to each weaving space the marionette was only adapted to select and 10 drive one shuttle at a time in a group of superposed shuttles, as one such shuttle serving to supply ground weft and the others figure weft; in other words, only one fabric could be woven at a time. If the character of the fabric to be 15 woven required with ground weft only one figure weft, and hence the driving of only two of the superposed shuttles, the other two shuttles remained idle, so that in such case the loom operated at only one-half its capacity.

According to this invention it is possible to use all four superposed shuttles but in the weaving of one fabric; or to use all four shuttles, weaving two fabrics at a time, the shuttles being active in pairs alternately entering the warp 25 sheds for such fabrics; or to use three or even four shuttles each constantly active relatively to a given one of three or four sheds.

In the drawings,

Fig. 1 is a front elevation of one end portion of 30 a loom embodying the improved marionette partly in section and partly broken away;

Fig. 2 is a left side elevation of the marionette;

Fig. 3 is a section of what is shown in Fig. 2 but in the plane 3—3 of Fig. 4, certain parts appearing in elevation;

Figs. 4 and 5 are sections as viewed respectively to left and right from the central vertical plane of Fig. 3;

Fig. 6 is a side elevation of the shifter; and

Fig. 7 a front elevation of one of its pickers.

1 is the main batten above which is the auxiliary batten structure comprising the lower and upper rails 2a and 2b and the shuttle blocks 3 connecting the rails and having equally spaced 45 superposed races guiding the shuttles 4a—4b—4c—4d. There will usually, of course, be a number of the blocks and hence of the sets of shuttles. In each rail is a pair of racks 5 (one behind the other) which through pinions, as 6, 50 drive the shuttles, the two lower racks the shuttles 4a—4b and the two upper racks the shuttles 4c—4d, such being well known. Also well known are the pairs of cords 7, the cords of each pair being connected to a rack and crossing each 55 other and extending around pulleys 8 and then

upwardly. To change the elevation of the auxiliary batten structure, and thus bring any one shuttle into line with the warp shed, of which there is assumed to be but one, there is the usual pattern-controlled means 9.

The following parts of the marionette are also known:

The stick-guiding box comprising two housings 10 joined in spaced relation by transverse members 11, they having their inner or adjacent sides open and a space 12 between them and each having vertical equally spaced partitions 10a, providing grooves, and vertical slots 13 in their outer walls open to the grooves. The box is supported on the main batten by a standard 14 and is therefore fixed against vertical displacement. In Fig. 1 the auxiliary batten structure is at its upward limit of movement, the loom frame F, standard 14 and a portion of means 9 being broken away. In effect a part 20 of the auxiliary batten structure is a frame comprising rods 15 upstanding from the top rail 2b (being reinforced by brackets 15a on such rail) and a cross-head 16, the rods being slidable in guides 17 projecting from the box. In the cross-head are journaled pulleys 18 and over these respectively extend cords 19, one to each pair of cords 7, and to the ends of each cord 19 are connected two of the sticks 20, they being respectively connected to the ends of cords 7. In short, 30 each pair of cords 7, the corresponding cord 19 and two sticks form a flexible rack-moving train which extends over a pulley 18 and, including a stick in each housing of the box, has its ends crossed and attached to a rack, wherefore movement of one stick or the other downwardly moves the rack one way or the other, the other stick rising. Each stick contains in its lengthwise slot a pawl 21 pivoted at its lower end and movable from retracted position in the stick to a position 40 in which its finger 21a projects from the stick into the path of a shifter which reciprocates constantly up and down in the slot 12, the pawl being normally held retracted by a spring 22 on the stick. The sticks of each group are stepped at intervals, 45 equal to those of the shuttle spacing, with the one nearest the observer in Fig. 1 the highest. It is usual to provide at the outer sides of the housings of the box and in the same horizontal plane two bars, such as 23, one for each stick-group, and on each such bar to provide four springs, such as 24, which reach into the respective slots 13, into which, further, may reach the humps shown on the backs (Fig. 3) of the pawls when the pawls are retracted. According to the 50 55

elevation to which the auxiliary batten structure and hence the mentioned pulley-carrying frame and trains are moved so the pawls of sticks of some one train will be brought to position to be subject to the action of corresponding springs 24 (to wit, to move the pawls against the tension of springs 22 into the path of the mentioned shifter). In the position assumed, the auxiliary batten being fully raised, the most remote complementary sticks in Fig. 1 are subject to the action of their controllers formed by the springs 24, wherefore (Fig. 3) on every other downward stroke of the shifter the left-hand stick will be pushed down and on the remaining downward strokes the right-hand stick will be pushed down, thus to reciprocate the shuttles actuated from these two sticks; when the auxiliary batten structure is moved to any of the other positions in which some shuttle will be aligned with the (single) warp shed two other complementary sticks will be positioned so as to be subject to their controllers and the corresponding shuttle will be actuated. With the mechanism thus constructed the loom can weave at a time only one fabric (or a single bank of fabrics, assuming that as usual there are a number of shuttle blocks and sets of shuttles).

Now according to this invention, given a four-way marionette (by which I mean one of the class herein set forth having four shuttle-driving trains), the box thereof has means to support eight controllers in two sets of four each and with such sets respectively adjacent the two stick-groups and with all the controllers of each set either in what I term the primary plane (being the plane occupied by the already mentioned four controllers), or the odd-numbered controllers of each sets in said plane and the even numbered controllers in a secondary and higher plane, or the first and third controllers in each set in said primary plane and the second and fourth controllers in a still higher or tertiary plane. Thereby the loom is adapted for the weaving of two fabrics at once as well as only one, and in weaving two fabrics at once the shuttles can be driven in pairs comprising either 4a—4b and 4c—4d or 4a—4c and 4b—4d.

That is, another bar 25 is arranged to cross the slots 13 of each set above the bar 23 and both these bars are provided with holes x, the lower bar with four such holes respectively opposite the four slots and the bar 25 with two such holes respectively opposite the second and fourth slots, always reading from the front of the box.

Further, another bar 26 is arranged to cross the slots of each set above bar 25 and this has holes x respectively opposite the third and fourth slots. If the loom is to operate with one shuttle at a time being driven four controllers 24 are removably secured to bar 23 by screws 28 tapped into the holes x of such bar, the controllers being then all in the mentioned primary plane I. If the loom is to operate with the shuttles driven in pairs 4a—4b and 4c—4d then the second and fourth controllers are removed from the bar 23 and secured by the screws to bar 25 opposite the second and fourth slots, being then in what I term the secondary plane II. (Of course, to change the drive from either shuttle pair to the other will in this case require a vertical displacement of the auxiliary batten structure equal to the spacing of the two shuttles, the sheds having the vertical spacing indicated at A—A). If the loom is to operate with the shuttles driven in the pair 4a—4c and 4b—4d then the third and fourth

controllers are transferred to the bar 26 opposite the third and fourth slots, being secured by the screws 28 and being then in what I term the tertiary plane III. (In this case, to change the drive from either shuttle pair to the other will require a vertical displacement of the auxiliary batten structure of but one shuttle space, the sheds having the vertical spacing indicated at B—B). It is assumed, and as will appear, that the shifter is constructed to catch stick-pawls projecting into space 12 at whatever elevation or elevations. The vertical spacing of the planes I, II and III is the same as that of the shuttles.

It may be desired to drive three or even all four shuttles at a time. In either case, with another bar 27 provided above the bars already referred to, the four controllers would be secured to the four bars and opposite the respective slots, beginning with bar 23 and the first slot.

It has been assumed heretofore that the selecting affects only the sticks, to wit, as determined by some selected arrangement of the controllers alone. But the shifter may be made to modify the selection, and for this purpose will be constructed as follows:

It has a body portion 29 having a bore forming a guideway receiving a stationary rod 30 on which the shifter constantly is reciprocated from some going part of the loom through a link 31, said body portion having four superposed bars 32 30 spaced the same as the superposed shuttles. On each bar are pickers or catching portions 33 each of the binary form shown by Fig. 7 (so as to catch the pawl-fingers of complementary sticks as the shifter reciprocates in space 12); also on each bar is a spacer 34. The pickers and spacers are removably held on the bars by cotter-pins 35.

Various possibilities exist in the use of such a shifter. For one example, assume that there are four controllers on the bar 23 but that the four pickers shown have been left arranged opposite the respective slots 13 but with the odd-numbered ones on the lowest shifter bar and the even-numbered ones on the next lowest shifter bar. Then when the stick-groups stand at one elevation (or with the whole number of sticks in each group in position to be caught by the shifter) such first and third sticks will be moved and when the stick-groups are moved to the next elevation (or with the second and fourth sticks in each group in position to be caught by the shifter) such second and fourth sticks will be moved.

Or, as a further example, assume that there are again four controllers on bar 23 but that the four pickers have been left arranged as shown in Fig. 6. At any one elevation of the sticks the pawl of only one stick from each group will at any time be in position to be engaged by the shifter, all the other pawls being in retracted positions. This would be the condition for using all four shuttles in the weaving of a single fabric.

In the foregoing I have treated the order of the sticks, controllers, etc., as reading from the front of the box merely to facilitate explanation of the mechanism; the appended claims are to be understood as not limited in this respect.

Having thus fully described my invention, what I claim is:

1. A marionette box for a four-way marionette having means to support two sets of four stick-pawl controllers respectively operatively adjacent to the two stick-groups of the marionette and with either all of the controllers of each set in the lowest of three superposed equidistant planes, or with the odd-numbered controllers of each

set in said plane and the even-numbered controllers of each set in the intermediate one of said planes, or with the first and second controllers of each set in said lowest plane and the third and fourth controllers of each set in the highest of said planes.

5. 2. A marionette box for a four-way marionette having means to support two sets of four stick-pawl controllers respectively operatively adjacent to the two stick-groups of the marionette and with either all of the controllers of each set in the lowest of three equidistant planes, or with the odd-numbered controllers of each set in said plane and the even-numbered controllers of each set in the intermediate one of said planes.

10. 3. A marionette box for a four-way marionette

having means to support two sets of four stick-pawl controllers respectively operatively adjacent to the two stick-groups of the marionette and with either all of the controllers of each set in the lowest of three superposed equidistant planes, or with the first and second controllers of each set in said plane and the third and fourth controllers of each set in the highest of said planes.

15. 4. A shifter for a marionette including a body portion having a guideway and a plurality of bars 10 extending cross-wise, and spaced from each other lengthwise, of the guideway, and a group of elements removably arranged on each bar and each including a picker and spacers.

FRANK W. PRESTON.
